ROBERT D. DUNCAN, JR., OF EAST ORANGE, NEW JERSEY, ASSIGNOR, BY MESNE ASSIGNMENTS, TO FEDERAL TELEGRAPH COMPANY, A CORPORATION OF CALIFORNIA

POLYPHASE ELECTRON-TUBE GENERATOR

Application filed June 28, 1927. Serial No. 202,081.

My invention relates broadly to circuits for the generation of high frequency current and more particularly to a generator or polyphase high frequency current.

5 One of the objects of my invention is to provide a system for the generation of polyphase high frequency current from an initial source of direct current.

Another object of my invention is to provide circuits for the conversion of direct current into polyphase high frequency current without the employment of a large amount of apparatus or complex electrical circuits.

10 Other and further objects of my invention will be understood from the specification hereinafter following by reference to the accompanying drawing which diagrammatically illustrates the circuit arrangement of my invention.

15 Hitherto in the art of generating polyphase high frequency current where the three electrode electron tube is employed, it has been necessary to generate first single phase current, then by means of special circuits in combination with single phase electron tube amplifiers to convert from single phase into polyphase current. A disadvantage of such arrangement is the more or less complex nature of the circuits involved and the relatively large number of electron tubes required.

20 My invention contemplates a form of multi-electrode electron tube and associated circuits by means of which polyphase and in particular three phase alternating current of any desired frequency may be generated directly without the use of a source of single phase current and intermediate phase displacing circuits.

25 In my co-pending application S. N. 88,279, filed Feb. 15, 1926, there has been disclosed a type of multi-element electron tube within which a rotating electric field is established for the purpose of converting from single phase to polyphase alternating current. In the present invention a similar type of electron tube is employed utilizing the feature of a rotating electric field or electron stream which by means of the tube and circuit arrangement employed converts directly from

direct current to polyphase alternating current. Referring to the drawing, I have shown a tube and circuit for generating three phase alternating current, the numeral 1 represents a filament electrode here shown in 55 the form of a straight wire which may be of material commonly employed for this purpose. Surrounding filament 1 and concentric therewith are three grid electrodes 2, 3, and 4, which are angularly displaced around the filament by 120°. Grids 2, 3 and 4 are shown to be of lattice construction and are separated from one another by spaces 5, 6 and 7. Surrounding both filament and grid electrodes are three plate electrodes 8, 9, 10 60 which are also concentric with the filament and are angularly displaced around the filament by 120°. Both grid and plate electrodes are shown for convenience, to be in the form of arcuate segments. This however, need not necessarily be the case, as they may take any desirable form as long as they are symmetrically positioned around the filament and displaced by appropriate angles. Filament 1, grids 2, 3, 4, plates 8, 9, 10 are 65 appropriately mounted and contained within a hermetically sealed vessel 11, which is assumed to be evacuated by any of the well-known processes, in order to obtain an electron discharge from filament 1. Connections 70 12 and 13 are brought out from within vessel 11 from the two ends of filament 1 and connect with battery 14, the negative terminal of which is grounded at 15. Battery 14 serves to render the filament incandescent for the 75 production of electrons. Additional connections 16, 17, 18 respectively from grids 2, 3, 4, are brought out of vessel 11. A third set of leads 19, 20, 21 connecting respectively with plates 8, 9, 10 are brought out from 80 vessel 11. Lead 19 connects through condenser 22 to circuit 23, composed of inductances 24, 25 and variable capacity 26. In a similar manner, leads 20 and 21 respectively connect through condensers 27 and 28 to circuits 29 and 30, composed of inductances 31, 32 and 33, 34 and capacities 35 and 36. Circuits 23, 29 and 30 are grounded at 15. Inductively coupled to inductances 24, 31 and 33 are respectively inductances 37, 38, 39 85 90 95 100

50 55 60 65 70 75 80 85 90 95 100

which are themselves connected in closed delta. From the apexes of the delta extend leads 16, 17 and 18 connected respectively with grids 2, 3, and 4. Connected in star to the apexes of delta connected inductances 37, 38, 39 are grid leak resistances 50, 51, 52, the common point of which is grounded through the grid biasing battery 53. Inductively coupled with inductances 25, 32, 34 are additional inductances 40, 41, 42 which together with variable portions 43, 44, 45 are connected in closed delta, from the apexes of which connections are made through condensers 46, 47, 48 to the three phase load, here shown to be a three phase transmission line 49. Plates 8, 9, 10 receive their requisite positive voltage from source 60 here shown to be a direct current generator, the negative terminal of which is grounded at 15. The positive terminal connects to plate leads 19, 20, 21 through choke coils 61. It will be noted that circuits 23, 29, 30 are interconnected through ground connection 15 in Y with respect to filament 1 also grounded at 15, while the circuit composed of inductances 37, 38, 39 is connected in closed delta. The ground 15 serves as a common point of connection.

The method of functioning of the arrangement of the drawing is as follows: The filament 1 is rendered incandescent by passage of current from battery 14. An electron field is therefore established in the evacuated space surrounding the filament. When the plates 8, 9, 10 are charged positively by closing the circuit of voltage source 60, a stream of electrons is drawn to each of plates 8, 9, 10 in the manner usual to any type of three electrode tube. At the same time the closing of the plate circuit will establish transient oscillations in each of circuits 23, 29, and 30; the frequency of these transients will correspond to the natural frequency of their circuits, here assumed to be substantially the same. By virtue of the coupling between inductances 24—37, 31—38 and 33—39, transient voltages are established in grid inductances 37, 38, 39. Now it is observed that inductances 37, 38, 39 are connected in closed delta, viz, from a closed circuit and in accordance with Kirchoff's law the vector sum of the voltages induced in the circuit must equal zero. Imposing the restriction that the transient voltage induced in inductances 37, 38, 39 be substantially equal, and in view of Kirchoff's law noted above, it is evident from the fundamental theory of three phase alternating currents that the equal transient voltages set up in 37, 38, 39 will differ in phase by substantially 120 electrical degrees, and therefore because of connections 16, 17, 18 to grids 2, 3, 4 there will be initially established between these grids transient voltages differing in phase by 120°. Focussing attention now on the multielectrode tube, it has been demonstrated in co-pending application

88,279, filed Feb. 15, 1926, that a three phase electron field surrounding the filament 1 will cause the electrons in the evacuated space surrounding filament 1 to revolve around the filament and impinge cyclically upon plates 8, 9, 10. Finally, fulfilling the well-known conditions for sustained oscillations which must exist between any three electrode tube and its input and output circuits the attenuation of the transient voltages and currents of circuits 23, 29, 30 and 37, 38, 39, may be made negative, that is sustained or undamped currents established and maintained in these circuits; furthermore, the currents in circuits 23, 29 and 30 will differ in phase by substantially 120°; or a three phase electron tube generator is obtained. Due to the coupling between inductances 25—40, 32—41, and 34—42, three phase currents are established in the three phase transmission line 49.

The circuit arrangements of my invention have been found to be efficient in operation and highly practical in view of their simplicity. The combination of the closed delta connected grid inductances and the Y connected plate circuits provides for stabilized operation of the polyphase system at a substantially constant frequency.

While I have described my invention in one of its preferred embodiments, I desire that it be understood that modifications may be made and that no limitations upon my invention are intended other than are imposed by the scope of the appended claims.

What I claim as new and desire to secure by Letters Patent of the United States is as follows:

1. In a system for generating polyphase high frequency current, an electron tube having a cathode and a plurality of grid and plate electrodes disposed adjacent thereto, means for heating said cathode, a closed delta circuit connecting said grid electrodes, a Y connected circuit connecting said plate electrodes, a load circuit coupled with said Y connected circuit and coupling means between said closed delta circuit and said Y connected circuit.

2. A system for generating three phase high frequency current comprising an electron tube having a cathode, a plurality of grid electrodes and a plurality of plate electrodes, each of said grid electrodes displaced 120° with respect to each other, and each of said plate electrodes displaced 120° with respect to each other around said cathode, a set of inductances connected in delta and connected with said grid electrodes, a separate set of inductances connected in Y and connected with said plate electrodes, a work circuit and means coupling said Y connected inductances with said work circuit and with said delta connected inductances.

3. A system for generating three phase high frequency current comprising an elec-

- tron tube having a cathode, a plurality of grid electrodes and a plurality of plate electrodes, each of said grid electrodes displaced 120° with respect to each other, and each of said plate electrodes displaced 120° with respect to each other around said cathode, a set of inductances connected in delta and connected with said grid electrodes, a set of circuits each including a pair of inductances and a capacity, with a Y connected circuit including selected ones of said inductances and said plate electrodes, a work circuit and coupling means between the inductances of said Y connected circuit, said work circuit and said delta connected circuit. 70
- 10 4. A system for generating three phase high frequency current comprising an electron discharge tube including a cathode and sets of independent grid and plate electrodes displaced 120° around said cathode, means for heating said cathode, a delta connected circuit including said grid electrodes, a Y connected circuit including said plate electrodes and means coupling said circuits for the production of three phase high frequency oscillations. 80
- 15 5. A system for generating three phase high frequency current comprising an electron discharge tube including a cathode and sets of independent grid and plate electrodes displaced 120° around said cathode, means for heating said cathode, independent inductance elements connected in delta, with connections from the apexes of said delta to each of said grid electrodes, a tuned circuit coupled with each of said inductance elements, a Y connected circuit including said tuned circuits, a connection between each of said tuned circuits and one of said plate electrodes and a work circuit coupled with said tuned circuits for receiving three phase high frequency oscillations developed in said aforementioned circuits. 90
- 20 6. A system for generating three phase high frequency current comprising an electron discharge tube including a cathode and sets of independent grid and plate electrodes displaced 120° around said cathode, means for heating said cathode, a plurality of inductance elements arranged in delta and connected with said grid electrodes, a plurality of independent tuned circuits each connected to one of said plate electrodes, each of said tuned circuits being independently coupled with a selected one of said inductance elements for the establishment of transient oscillations therein for setting up sustained three phase high frequency oscillations in said connected circuit. 100
- 25 7. A system for generating three phase high frequency current comprising an electron tube having a cathode and sets of independent grid and plate electrodes displaced 120° around said cathode, a set of inductances connected in delta and connected with said 105
- 30 8. A system for generating three phase high frequency current comprising an electron discharge tube including a cathode and sets of independent grid and plate electrodes displaced 120° around said cathode, means for heating said cathode, independent inductance elements connected in delta, with connections from the apexes of said delta to each of said grid electrodes, a tuned circuit coupled with each of said inductance elements, a Y connected circuit including said tuned circuits, a connection between each of said tuned circuits and one of said plate electrodes and a work circuit coupled with said tuned circuits for receiving three phase high frequency oscillations developed in said aforementioned circuits. 110
- 35 9. A system for generating three phase high frequency current comprising an electron discharge tube including a cathode and sets of independent grid and plate electrodes displaced 120° around said cathode, means for heating said cathode, a plurality of inductance elements arranged in delta and connected with said grid electrodes, a plurality of independent tuned circuits each connected to one of said plate electrodes, each of said tuned circuits being independently coupled with a selected one of said inductance elements for the establishment of transient oscillations therein for setting up sustained three phase high frequency oscillations in said connected circuit. 115
- 40 10. A system for generating three phase high frequency current comprising an electron discharge tube including a cathode and sets of independent grid and plate electrodes displaced 120° around said cathode, means for heating said cathode, a plurality of inductance elements arranged in delta and connected with said grid electrodes, a plurality of independent tuned circuits each connected to one of said plate electrodes, each of said tuned circuits being independently coupled with a selected one of said inductance elements for the establishment of transient oscillations therein for setting up sustained three phase high frequency oscillations in said connected circuit. 120
- 45 11. A system for generating three phase high frequency current comprising an electron discharge tube including a cathode and sets of independent grid and plate electrodes displaced 120° around said cathode, means for heating said cathode, a plurality of inductance elements arranged in delta and connected with said grid electrodes, a plurality of independent tuned circuits each connected to one of said plate electrodes, each of said tuned circuits being independently coupled with a selected one of said inductance elements for the establishment of transient oscillations therein for setting up sustained three phase high frequency oscillations in said connected circuit. 125
- 50 12. A system for generating three phase high frequency current comprising an electron discharge tube including a cathode and sets of independent grid and plate electrodes displaced 120° around said cathode, means for heating said cathode, a plurality of inductance elements arranged in delta and connected with said grid electrodes, a plurality of independent tuned circuits each connected to one of said plate electrodes, each of said tuned circuits being independently coupled with a selected one of said inductance elements for the establishment of transient oscillations therein for setting up sustained three phase high frequency oscillations in said connected circuit. 130
